CLAIM

The ornamental design of a storage container, as shown and described.

DESCRIPTION

FIG. 1 is a side perspective view of a storage container, showing my new design;

FIG. 2 is a top plan view of the storage container;

FIG. 3 is a bottom plan view of the storage container;

FIG. 4 is a left side elevational view of the storage container as shown in FIG. 1;

FIG. 5 is a right side elevational view of the storage container as shown in FIG. 1;

FIG. 6 is a rear elevational view of the storage container as shown in FIG. 1;

FIG. 7 is a front elevational view of the storage container as shown in FIG. 1;

FIG. 8 is an exploded side perspective view thereof; and, FIG. 9 is an inverted exploded side perspective view thereof. The broken lines shown in FIGS. 8 and 9 are for the purpose of illustrating environment and form no part of the claimed design.
